UNITED STATES PATENT OFFICE.

SAMUEL L. BELKNAP, OF LOS ANGELES, CALIFORNIA.

COIN-CONTROLLED SAFE.

Application filed August 17, 1926. Serial No. 129,711.

This invention relates to improvements in safes.

An object of this invention is to provide an improved safe which is coin controlled in that the safe cannot be locked without employing a coin, and after the safe has once been locked, it cannot be opened except by an authorized person.

1 Another object of this invention is to provide a safe which has a lock operable by a key and to provide a coin controlled mechanism which will prevent the safe from being locked unless a coin is employed and which will also prevent the withdrawal of the key unless the safe is locked.

13 A further object of this invention is to provide a safe of cheap, simple and durable construction which can be employed in various public localities, such as in Pullman cars, 20 steamships, stores or the like, and which can be used for safely checking or depositing articles of value.

A still further object of this invention is to provide a safe which is operable by a coin to permit the safe to be locked, and to provide a register or counting means for counting the coins deposited in the safe to permit the safe to be locked.

With the foregoing and other objects in view which will be made manifest in the following detailed description and specifically pointed out in the appended claims, reference is had to the accompanying drawings for an illustrative embodiment of the invention, wherein:

Figure 1 is a perspective view of the improved safe, the door being shown in open position.

Fig. 2 is a perspective view taken from a different angle than Fig. 1, also illustrating the safe in open position,

Fig. 3 is a perspective view of the safe showing the door in closed position,

Fig. 4 is a vertical section taken substantially on the line 4-4 of Fig. 3,

Fig. 5 is a vertical section taken substantially on the line 5-5 of Fig. 4.

Fig. 6 is a vertical section taken substantially on the line 6—6 of Fig. 4, the back panel or back wall of the door being shown as having been broken away and removed,

Fig. 7 is a view similar to Fig. 6 illustrating the bolt as having been shifted from unlocking position to locking position,

55 Fig. 8 is a vertical section taken substantially on the line 8-8 upon Fig. 4, and

Fig. 9 is a perspective view of the key.

Referring to the accompanying drawings wherein similar reference characters designate similar parts throughout, the improved coin controlled safe consists of a container 10 having top, bottom, side and back walls and which may be imbedded in a wall. The container, if desired, can be formed in any suitable manner, but if it is to be imbedded in a wall, which is the preferred construction, it is preferably provided around its front or open side with a marginal flange 11. A hinged door is provided for the safe shown as having a front wall 12, which is preferably formed of heavy steel plate. A suitable band 13 is arranged about the door and is secured thereto, such as by spot-welding, thus providing flanges which extend rearwardly from the top and sides of the door. The door is also provided with a back wall 14 having top, bottom and side flanges 15 adapted to fit within the flanges provided by the band 13.

A lock is provided for the door which consists of a central stationary cylinder or body part 16 having a key-way 17 formed therethrough. About this stationary cylinder or body part there is disposed a rotatable part or cylinder 18 having a handle 19 secured to its forward end which is disposed forwardly of the face or front wall 12 of the door. A disc 20 is fastened to the rear end of the movable part or rotatable cylinder 18. The interior surface of the cylinder 18 fits snugly against the exterior surface of the stationary cylinder or body part 16. A plurality of small plates are arranged one behind the other in the key-way 17. These plates provide tumblers for the lock and are indicated at 21. Each plate has an aperture 22 formed therein for the reception of the key and is equal in length from top to bottom to the diameter of the stationary cylinder or body part 16. The position of the aperture 22 in each plate varies with respect to the ends of the plate. On the interior surface of the cylinder 18 at the top and bottom thereof there are formed longitudinal grooves which are equal in width to the width of the key-way or approximately so.

Normally when the key is out of the key-way, the various tumblers or plates 21 fall to the bottom of the key-way and have their lower ends entering the bottom groove, thus locking the cylinder 18 against rotation relatively to the stationary part 16. If desired, suitable springs may be employed, which will urge some of the plates to have their upper 105 110

ends enter the upper groove, thus assisting in locking the parts 16 and 18 against relative rotation. When a key is inserted into the key-way, the serrations on the key engage the 5 top and bottom edges of the apertures 22, thus causing all of the plates to be aligned so that their upper ends are just even with the top of the stationary cylinder 16 and their bottom ends are just even with the bottom surface 10 of the stationary cylinder 16. When in such position the cylinder 18 can be rotated by the handle 19 to rotate the disc 20. When the cylinder 18 has been rotated from the position shown in Fig. 8 so that the grooves on 15 the interior surface of the cylinder 18 are no longer registering with the top and bottom of the key-way, it will be appreciated that the plates or tumblers 21 cannot be moved. They will accordingly hold the key in the key-way, 20 permitting the upper and lower ends of the tumblers to enter them.

A bracket 23 is provided consisting of a section of sheet metal having three portions bent forwardly therefrom and then outwardly providing lugs 24 which receive screws 25 30 fastening the bracket to the back of the forward wall 12 of the door. In this bracket there is slidable a bolt 26 having a pin 27 slidable in the slot 28 formed in the bracket. A lug is struck out of the body of the bracket, 35 as indicated at 29, and a coil spring 30 joins the lug to the pin 27, thus urging the bolt 26 at all times into retracted position. About one-half of the bolt on its forward side is cut away, as indicated at 31, to receive the disc 40 20. The disc is provided on its back side with an arcuate projection 32 located adjacent its periphery. This projection constitutes a cam which is engageable upon the inside end of the bolt. A semi-circular recess 33 is 45 formed in the peripheral surface of the disc constituting a coin receiving pocket adapted to receive a coin from a coin chute 34 fastened to the front wall 12 and which has its entrance located on the edge of the door through the 50 band 13, as clearly shown in Fig. 1. The disc 20 is normally in the position shown in Fig. 6 and when in such position the cylinder 18 is rotated from the position shown in Fig. 8 so that when the bolt 26 is retracted and the 55 door can be opened, the key is retained in the key-way by the tumblers.

When it is desired to use the safe, the person wishing to use it places his articles of value therein, and then deposits a coin 60 in the upper end of the coin chute 34. This coin chute causes the coin to fall into the coin pocket 33. When this has been done, the handle 19 can then be turned, rotating the cylinder 18 and rotating the 65 disc 20. The projecting portion of the coin

engages the shoulder 35 on the bolt, and causes the bolt to slide from the position shown in Fig. 6 to the position shown in Fig. 7. After the bolt has been caused to slide, the arcuate cam 32 can pass behind the 70 end of the bolt and will keep the bolt in thrown position against the action of the coil spring 30. This permits the handle 19 to be rotated further so that the coin pocket will pass below the bottom of the bolt, allowing the coin to drop out of the coin pocket into a coin receiving receptacle 36. When the handle 19 has been thus completely turned, its movement being limited by a pin 37 on the projection 32 engaging the bottom 75 edge of the bracket, it will have caused the cylinder 18 to have assumed a position with respect to the stationary cylinder or body part 16 as shown in Fig. 8. When in this position the key can be removed. When the 80 person wishes to withdraw the articles from the safe, he can do so by again inserting the key into the cylinder 16, causing the tumblers to be shifted properly so that the handle 19 can turn the cylinder 18. The handle 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 of the stationary cylinder is fastened to the bracket 23 as by screws 42 firmly connecting the various parts of the lock together.

From the above described construction it will be appreciated that a novel coin controlled safe is provided of simple yet durable construction requiring that a coin be employed before the safe can be used and safe-guarding against the loss of keys. If 10 the safe is to be employed in a Pullman car, the key employed indicated at 43 is preferably provided with a wrist encircling member 44 adapted to be positioned about the wrist of the person using the safe. By keeping 15 the key thus fastened about the wrist, it is an effective safeguard against the theft and also a safe-guard against the person renting the safe forgetting that he has his valuable articles therein and departing from 20 the Pullman car without them.

It will be understood that various changes may be made in the details of construction without departing from the spirit or scope of the invention as defined by the appended 25 claims.

I claim:

1. A coin controlled safe comprising a container having a door, a stationary member having a key-way therein mounted on the 30 door, a movable part mounted on the door, a bolt adapted to be moved by the movable part, tumblers preventing the movable part from being moved unless the proper key is inserted in the key-way, said tumblers being so arranged as to prevent withdrawal of the key 35 from the key-way when the bolt has been moved into unlocking position by said movable part, and coin controlled means permitting the bolt to be thrown by said movable 40 part only when a coin is employed.

2. A coin controlled safe comprising a container having a door, a stationary member having a key-way therein mounted on the door, a rotatable cylinder rotatably mounted 45 upon the door about the stationary member, a bolt adapted to be moved by the rotatable member, tumblers preventing movement of the movable part unless the proper key is inserted in the key-way, said tumblers being so arranged as to prevent withdrawal of the key 50 from the key-way when the bolt has been moved into unlocking position by said rotatable member, and coin controlled means permitting the bolt to be thrown by said rotatable member only when a coin is employed.

3. In a safe, a door, a stationary part mounted thereon having a key-way therein, a rotatable part rotatable about the stationary part, a coin-pocket in said rotatable part, tumblers preventing the rotatable part from 60 being rotated unless the proper key is inserted in the key-way, and means for maintaining the door in closed or locked position operable by rotating the rotatable part when a coin is in said coin-pocket, said tumblers

being so arranged that the key can only be withdrawn from the key-way when the door is in locked position, and when the key is withdrawn, the rotatable part cannot be rotated.

4. In a coin controlled lock, the combination of a locking bolt, a rotatable part providing a coin receiving pocket adapted to partially receive a coin, and lock controlled means normally preventing, but when properly operated permitting the rotatable part to be moved so as to move the coin through an arc in the plane of the coin and cause its projecting portion to engage and move the locking bolt.

5. In a coin controlled lock, the combination of a locking bolt, a rotatable disc providing a coin receiving pocket in its periphery adapted to partially receive a coin in a position parallel to the plane of the disc, lock 80 controlled means permitting said rotatable disc to be rotated to cause the projecting portion of the coin to produce movement of the locking bolt, and an arcuate cam carried by the rotatable disc adapted to be moved thereby into engagement with the locking bolt to maintain the bolt in its moved position.

6. In a coin controlled lock, the combination of a stationary key receiving part, a movable part, means preventing the movable part 95 from being moved unless the proper key is inserted in the key receiving part, a locking bolt, and coin controlled means permitting the locking bolt to be moved by the movable part when a coin is employed.

7. In a coin controlled lock, the combination of a stationary key receiving part, a movable part, means preventing the movable part from being moved unless the proper key is inserted in the key receiving part, a locking 100 bolt, and coin controlled means permitting the locking bolt to be moved by the movable part when a coin is employed, the first mentioned means being so constructed as to prevent the removal of the key from the key receiving part except when the locking bolt is in locking position.

8. In a coin controlled lock, the combination of a stationary key receiving part, a rotatable part rotatable thereabout, means preventing the rotatable part from being rotated unless the proper key is inserted in the key receiving part, a locking bolt, and coin controlled means permitting the locking bolt to be moved by the rotatable part when a coin 115 is employed.

9. In a coin controlled lock, the combination of a stationary key receiving part, a rotatable part rotatable thereabout, means preventing the rotatable part from being rotated unless the proper key is inserted in the key receiving part, a locking bolt, and coin controlled means permitting the locking bolt to be moved by the rotatable part when a coin 125 is employed, the first mentioned means being 130

so constructed as to prevent the removal of the key from the key receiving part except when the locking bolt is in locking position.

10. A coin controlled lock comprising a stationary key-way, a rotatable part rotatable about the stationary key-way, tumblers operatively associated with the key-way and rotatable part for serving to prevent rotation of the rotatable part unless the proper key is inserted in the key-way, a locking bolt, a rotatable disc associated with the rotatable part, there being a coin receiving pocket in the disc adapted to partially receive a coin and to move it upon rotation into engagement 15 with the locking bolt to move the locking bolt into locking position.

11. A coin controlled lock comprising a stationary key-way, a rotatable part rotatable

about the stationary key-way, tumblers operatively associated with the key-way and rotatable part for serving to prevent rotation of the rotatable part unless the proper key is inserted in the key-way, a locking bolt, a rotatable disc associated with the rotatable part, there being a coin receiving pocket in the disc adapted to partially receive a coin and to move it upon rotation into engagement with the locking bolt to move the locking bolt into locking position, and a cam carried by the rotatable disc engageable upon the locking bolt for maintaining the locking bolt in locking position after having been moved therein by the coin. 20 25 30

In testimony whereof I have signed my name to this specification.

S. L. BELKNAP.
